UNITED STATES PATENT OFFICE.

JOHN M. FINCH, OF MARYSVILLE, CALIFORNIA.

SEPARATOR.

SPECIFICATION forming part of Letters Patent No. 499,915, dated June 20, 1893.

Application filed December 24, 1892. Serial No. 456,257. (No model.)

To all whom it may concern:

Be it known that I, JOHN M. FINCH, a citizen of the United States, residing at Marysville, Yuba county, State of California, have 5 invented an Improvement in Separators; and I hereby declare the following to be a full, clear, and exact description of the same.

My invention relates to that class of machines for separating material composed of 10 particles of different specific gravities, in which a current of air is directed upon the falling material, said machines being known as air or gravity separators or purifiers, and particularly designed for separating or purifying middlings in flour mills.

My invention consists essentially in a rotating cage to which the material is fed, the periphery of said cage being so constructed as to retain and constantly raise and drop the 20 material, and of an open character to freely permit the passage of a current of air through it, and suitable means for creating and directing a current of air through the open periphery of said cage and against the constantly falling material whereby the latter is repeatedly subjected to said current.

It also consists in the particular construction and arrangement of the parts of the machine hereinafter described, and representing 30 the best form in which my invention is embodied. In this form is partially embodied the principle of the continuous or repeatedly used air current of the Patent No. 400,201, issued to me jointly with John R. Cross March 35 26, 1889, and upon which in one sense my present invention is an improvement.

The objects of my invention will hereinafter fully appear.

Referring to the accompanying drawings 40 for a more complete explanation of my invention,—Figure 1 is a cross section on the line $x-x$ of Fig. 2. Fig. 2 is a horizontal section on the line $y-y$ of Fig. 1. Fig. 3 is a longitudinal section on the irregular line $z-z$ of 45 Fig. 1.

A is a frame or stand in which is supported the downwardly directing main casing B, the walls of which extend lengthwise of the frame, and terminate with the innermost of 50 the double end walls a thereof, which said end walls form the passages a' through one of which the material is fed, and through an-

other of which it is discharged. Within the casing B is mounted the rotating cage. This is formed of end heads c , mounted upon a 55 shaft c' and having extending between them the inclined slats C which form the periphery of the cage. These slats are separated from one another, but the plane of the outer edge of one overlaps the plane of the inner edge of 60 the one in advance, whereby, though the whole periphery is of a character sufficiently open to permit the free passage of an air current, it will retain the material within it, on its uprising side. The arrow indicates 65 the direction of rotation of the cage, which rotation is imparted in any suitable manner, as from the pulley c^2 (Fig. 3) applied to the outer end of the shaft c' . The whole cage is slightly inclined in the direction of its length 70 as is shown in Fig. 3. The passage a' at the head delivers the material into the cage, and the passage a' at the foot receives it from the cage, the slats C being at the lower end cut away as shown at c^3 to permit the discharge 75 of the material therefrom.

The top of the casing B is provided with a hood b which extends down to the cage and terminates in a line a little in advance of the upper extremity of the vertical diameter of 80 the cage. Within the upper portion of this hood is a fan D, driven by suitable means as from the pulley d shown in Fig. 3. Under the fan is a segment shield d' which terminates in a partition E, provided with a swinging 85 valve F, operated by a handle f' on the outer end of its axis f . From the base of this partition springs a casing G which encircles the back and lower portion of the cage and extends up in front of it to about the horizontal 90 plane of the end of the hood, but separated from it. The course of the air current is indicated by the arrows.

In the bottom of casing B is a conveyer H for receiving and discharging the worthless 95 materials separated from the stock within the cage and dropped out of the air current in its course.

The operation of the machine is as follows: The overlapping slats are arranged in such a 100 manner that when the cage is revolved the material will slip or fall from one slat to another, and will be carried up to a point where the weight of the material will overcome the

friction upon the slats: and the rapidity with which the cage is revolved will largely determine this point. As the cage is inclined, it follows that the material introduced at the 5 high or head end will gradually work toward the foot or low end, and thereby making the slats narrower, as shown at c^3 , or by leaving the end open, it will discharge or pass out. The fan wheel above the cage has blades the 10 entire length, and will set in motion a current of air which will move with the fan until it meets the segment shield d' beneath whereby it is prevented from continuing with the fan, but is sent downward. If now the valve F is 15 closed as shown in Fig. 1, the air must pass down behind and under the casing G which partially encircles the cage, as described, thence up and over the end of said casing and down into the cage; thence up and out of the 20 cage and back to the fan, completing the circuit. Now, as the material to be treated is constantly falling from slat to slat upon the side of the cage, through which the air enters, it is evident that this air must pass through it, and any 25 light particles not heavy enough to withstand the force of the current will be carried upward and out of the cage and to the fan, passing over the fan and downward. Here the force of gravity and momentum will throw it 30 out of the current of air into the conveyer H, the air passing on in its circuit. What little dust may accompany it is so light that it will pass on with it and in no way interfere with the work to be accomplished. Now, if the valve 35 F be open, the air has a shorter passage and will take it in preference to the longer route and no air will pass through the cage. Therefore, by opening or closing this valve the amount of air passing through the cage may 40 be regulated at will.

The improvement embodied in this machine may be best made apparent by brief reference to other machines of this class, together with necessary comparisons.

45 In the machine heretofore mentioned as patented to Finch and Cross, the current of air as far as its continuous course is concerned, is used in a somewhat similar manner, but the material is fed into the current the entire 50 length, the air passes once through it, and then the material drops away.

55 It is a very difficult matter to so adjust the air current that it will remove all of the objectionable matter, and not carry away a considerable quantity of the material that should remain; for in many cases, particularly in flour mills, the difference in the gravity of the particles to be separated is slight, and any change of feed or variation of fan speed causes 60 the machine to work irregularly. This objection will apply with equal force to all machines of this class with which I am familiar. Now, if a weak current of air can be used, one that will not carry away anything but what 65 should be removed, and the material can be treated repeatedly until all has been removed that should be, an important and improved

result will have been reached. To do this (as in some machines) by increasing the number of times and places, the current is made to 70 intersect a descending stream of material, is open to the serious objection that the material removed by the later intersections has to pass and repass through the descending stream. On the other hand, if the material be subjected 75 to a number of operations by independent currents there arises the difficulty of separating the dust from the air, for while each current may be weak or light, the aggregate of all makes a strong current very difficult to 80 manage, and moreover to provide separate fans for each application involves space and expense.

In my machine the material fed into the cage is passed repeatedly through the same 85 current, but the material removed is taken from the air before it (the air) returns to its work, and the strength of the current is so slight that no trouble is experienced in taking away more than is desirable, or in dropping 90 the dust from the air. No feeding device is required and the machine is no more expensive to build, and takes no more space and power than others, while its work is better. It will be manifest, therefore, that the essential 95 feature of my machine is a rotating cage having its periphery sufficiently open to permit the free passage of the air current and yet so constructed as to retain and to repeatedly raise and drop the material, and this 100 feature is independent of any means for creating or directing the air current, or of the manner of disposing of the material removed. I do not, therefore, confine myself to the 105 means here shown for effecting this current, nor to the manner of its application, for it is not essential that the same air be returned to the cage, as fresh air may be introduced, and be blown away by the fan after it has performed its work. Nor do I wish to be restricted to the particular course of the operation 110 described, nor to the exact manner of using the cage, for it is obvious that the air may be passed through the cage from the opposite way, or it may be introduced at the 115 ends and emerge from the periphery or vice versa. These are but immaterial variations in details of arrangement which do not affect or alter the character of my invention.

Having thus described my invention, what 120 I claim as new, and desire to secure by Letters Patent, is—

1. In a separator the combination of the main casing, the rotating cage located therein having its periphery formed of separated 125 overlapping slats cut away at one end, the hood located above said cage the casing partially encircling the cage and forming with the hood an air passage intersecting the periphery of the cage on its uprising side, the 130 fan located in the hood the double end walls forming feed and discharge passages and the worm conveyer at the bottom of the main casing, substantially as herein described.

2. In a separator the combination of the main casing, a rotating cage therein to which the material is fed and having its periphery formed of separated overlapping slats, the 5 hood above the cage, the fan located therein the segment shield below said fan, the partition located in said hood below the shield, the swinging valve connected with said partition, the casing partially encircling the cage and

an air passage intersecting the periphery of 10 the cage, substantially as herein described.

In witness whereof I have hereunto set my hand.

JOHN M. FINCH.
